UNITED STATES PATENT OFFICE.

WILLIAM C. BOHRMANN, OF BELVEDERE, CALIFORNIA.

ABRASIVE DEVICE.

Application filed May 25, 1922. Serial No. 563,702.

To all whom it may concern:

Be it known that I, WILLIAM C. BOHRMANN, a citizen of the United States, and a resident of Belvedere, Marin County, State of California, have invented a certain new and useful Abrasive Device, of which the following is a specification.

The invention relates to an abrasive device and particularly to a device employing "steel wool" as the abrasive material.

An object of the invention is to provide means for making possible the mechanical use of steel wool in the industries and for facilitating its use in the household.

Another object of the invention is to provide a steel wool abrasive device for convenient household use.

The invention possesses other advantageous features, some of which, with the foregoing, will be set forth at length in the following description where I shall outline in full those embodiments of my invention which I have selected for illustration in the drawings accompanying and forming part of the present specifications. In said drawings I have shown several forms of devices embodying my invention, but it is to be understood that I do not limit myself to such forms, since the invention, as set forth in the claims, may be embodied in a plurality of other forms.

Referring to said drawings:—

Figure 1 is a perspective view of one form of device embodying my invention.

Figure 2 is a cross section through a modified form of the device.

Figure 3 is a cross section through another form of the device.

Figure 4 is a cross section through a further modified form of the device.

Figure 5 is a view of a modified form of the device; and, Figure 6 is a view of the abrasive device, showing its preferred form when it is to be secured to a moving element.

Fig. 7 is a view of the invention as applied to a rotary holder.

Steel wool is a very effective and efficient abradant, but, as far as I am aware, no means or devices have been provided for permitting optimum results to be obtained by its use. The steel wool is placed on the market in bulk form and in small bunches, and in using it in either form, it is neces-

sary to grasp a wad or bunch of it in the hand, and the user's hand, unless gloved, comes into direct contact with the steel wool.

This method of using steel wool is very objectionable to the users; for the stiff sharp particles of steel wool readily penetrate the skin of the user's hands, causing much discomfort and often setting up more or less irritation and soreness, as these small particles of steel wool act in and under the skin very much like a splinter or sharp thorn. In household use many housewives also object to using steel wool in any of its present forms because it likewise roughens the skin of the hands.

Furthermore, steel wool, in any of its present forms, is used wastefully and without obtaining the highest degree of efficacy latent in this abrasive and polishing agent, because the user, being obliged to clasp the steel wool directly in the hand, bunches it up in various rough shapes in order to be able to retain his grasp thereon, and in thus rolling and bunching up these pliable and loose forms of steel wool while using it, the steel wool is broken up and the broken particles and smaller bunches thereby separate from the original wad or bunch and are lost by falling away from it.

Therefore, in order to overcome the objections to the use of steel wool in its present forms as set forth above, and also in order to greatly extend the use of steel wool to many industries that require an abrasive or polishing agent to be applied by mechanically driven devices instead of by costly hand labor, I have provided a device employing steel wool as the abradant, which permits the material to be used without grasping it directly in the hand and which prevents excessive wastage of steel wool when in use.

In accordance with my invention, the bulk steel wool is preferably first put through a carding process, or other similar process which will draw the fibers into a continuous layer which is of approximately uniform density and thickness. For certain uses, the layer or strip is compressed or compacted by passing it between compression rollers, and for other purposes, the layer or strip may be twisted into rope-like form and several of the rope-like strands may be braided together, when desired.

These compacted strands, either in form

of strips, ropes or braids are then attached to firm prepared backings, of closely woven canvas, or other stout firm material, preferably by rows of machine stitching. By thus 5 stitching the steel wool, in any of its prepared forms preferably by fabric thread stitching to a firm backing, the material is not only disposed so that it may be used without objection, but the steel wool will be 10 held firmly together, nearly every fiber being securely attached by said stitching to the canvas or other backing, thus preventing wastage. The stiffness of the backing also prevents the material from being 15 bunched and broken up, thus further reducing wastage. For certain uses of this device I have found it advisable to spray that surface of the compacted strands of steel wool that comes into contact with the prepared backing, with liquid sodium silicate, varnish, shellac, liquid glue, or other similar 20 sizing or binding material, thus lending further rigidity and cohesion to the fibers of steel wool.

25 In Figure 1, I have shown a device for hand use, embodying my invention. This device comprises a backing 2, of canvas, or comparable material, stitched or otherwise fastened together at the center to form a grip or handle 3, extending outward from and integral with the backing. Secured within this grip, along its outer edge, is a length of rope 4 or similar material which lends bulk to the grip, so that it may be 30 more conveniently grasped. Secured to the backing 2, by the lines of stitching 5, is a pad or layer 6 of compacted steel wool, preferably extending for substantially the length of the backing. The backing is preferably of greater width than the pad or layer 6, thereby providing flexible flaps 7 along the sides, which project beyond the steel wool and prevent it from coming into contact with the user's hand. The form of 40 device shown by Figure 4 is intended for use in conjunction with a firm wooden or metal backing to which this device can be attached by means of the wide loose flaps projecting beyond the side edges of this device, and this device, when so combined with a suitable wooden or metal backing, is intended for use in rubbing down by hand, or abrading by hand, plane surfaces, or may be secured to a power driven element.

45 In order to render the canvas or other backing material less liable to distortion in use, and to prevent liquids used with the abradant from coming into contact with the canvas, I have found it advisable, for some 50 uses, to rubberize or otherwise render impermeable the surface of the backing which lies adjacent the steel wool including the same surface of said projecting loose flaps. In Figure 2, I have shown a layer 8 of rubber or comparable material arranged on the 55 surface of the backing. This rubber or other similar material is preferably applied to the backing in liquid or plastic form and the pad of steel wool is preferably stitched to the backing while the rubber material is still in plastic form, thus more firmly securing the steel wool to the backing.

60 It will be understood that the backing, as a whole, preferably consists of the outer fabric or flexible layer 2 and the interposed layer 8, which is formed of a flexible material substantially impervious to steel wool.

65 For kitchen and household use, it is often advantageous to use a detergent, such as soap, with the steel wool, to secure the desired results. It has been proposed heretofore to impregnate with soap a pad of steel wool having no other attachment, but I have found that the soap washes out of such pad, during the first few times that it is used, leaving only the steel wool remaining. In accordance with my invention, I propose not to combine the soap with the steel wool, but to arrange a layer of soap behind the steel wool, so that the water or other solvent used with the steel wool, will dissolve the soap slowly, when the device is being used, causing a soap solution to flow through the steel wool to the surface of the object being cleansed therewith. In Figure 3, I have shown one form of device in which a layer of soap 9, is interposed between the rubberized backing and the steel wool pad. The soap is preferably applied in plastic form before the steel wool is applied, and the stitching is then passed through the backing, the soap layer and the steel wool. To prevent the soap from being consumed too rapidly, when the device is dipped in water and then rubbed over a surface, and to prevent the fibers and particles of the steel wool from cutting off chips of the soap, as the device is used, I prefer to enclose the soap layer in a pervious envelope 10, formed of cotton gauze, cheese cloth or other comparable material. It is not essential that the envelope completely enfold the soap, since its function is primarily to separate the soap from the steel wool, but I prefer to fold the side edges of the pervious material over the side edges of the soap layer, so that they are positioned over the soap layer in such position as to be caught by one of the rows of stitching.

70 When the steel wool is to be used as an abradant in a power driven apparatus, the backing to which the compacted layer or strand is secured, may be of any desired dimensions, so that it may pass around a cylinder or drum or so that it may be readily attached to any suitable movable element. When used for these purposes, the grip 3 may be dispensed with, and the side flaps 7 may or may not be used, as desired and such pads would preferably be attached to

said revolving drums or cylinders by means of projections of backing material of suitable length extending beyond the two ends of the steel wool pad.

5 I claim:

1. An abrasive device comprising a backing of impervious material, a layer of compacted steel wool secured to said backing and flexible flaps extending from the sides 10 of said backing.

2. An abrasive device comprising a flexible backing, a compacted layer of steel wool stitched to said backing, a layer of flexible impervious material interposed between the 15 steel wool and the backing and a handle on said backing.

3. An abrasive device comprising a backing, a compacted layer of steel wool secured to said backing and a layer of soap interposed between said backing and layer. 20

4. An abrasive device comprising a backing, a compacted layer of steel wool secured to said backing, a layer of soap interposed between said backing and layer and a strip 25 of pervious material interposed between the soap and the steel wool.

5. An abrasive device comprising a flexible backing, a compacted layer of steel wool stitched to said backing and a layer of soap 30 interposed between the layer and the backing.

6. An abrasive device comprising a flexible backing, a compacted layer of steel wool stitched to said backing, a layer of soap interposed between the backing and the layer 35 and a strip of pervious material interposed between the soap and the steel wool.

7. An abrasive device comprising a flexible impervious backing, a compacted layer 40 of steel wool stitched to said backing, a layer of soap interposed between the backing and the steel wool and a strip of pervious material interposed between the soap and the steel wool.

45 8. An abrasive device comprising a flexible backing and a layer of steel wool im-

pregnated with a binder of sodium silicate, secured to said backing.

9. An abrasive device comprising a rectangular flexible backing folded on itself 50 and secured together along the center line thereof to form a handle and a layer of steel wool secured to said backing.

10. An abrasive device, comprising a flexible backing and a layer of steel wool permanently secured thereto, said wool being combined with a flexible binder slowly soluble in water. 55

11. An abrasive device comprising a flexible backing folded on itself and secured together 60 to form a handle for the device as an integral part of such backing, and a layer of steel wool permanently secured to said backing.

12. An abrasive device comprising a flexible backing which is folded on itself and secured together to form a handle for the device as an integral part of such backing, a layer of steel wool permanently secured to 65 said backing, and a layer of impervious flexible material interposed between the backing and the steel wool.

13. An abrasive device for permitting the use of steel wool without requiring contact 75 of the hand of the user with the steel wool comprising a flexible backing substantially impervious to steel wool fibers, a layer of steel wool permanently secured to said backing, and a hand grip extending across the center of said backing and secured to said 80 backing throughout its entire length.

14. An abrasive device comprising a flexible backing, a layer of steel wool, a layer 85 of flexible material impervious to steel wool interposed between the steel wool and the backing, said backing, impervious material, and steel wool being permanently secured together, and a handle permanently secured to said backing.

In testimony whereof, I have hereunto set 90 my hand.

WILLIAM C. BOHRMANN.
